CLAIM

The ornamental design for a luggage as shown and described.

DESCRIPTION

The file of this patent contains at least one drawing/photograph executed in color. Copies of this patent with color drawing(s)/photographs will be provided by the Office upon request and payment of the necessary fee.

FIG. 1 is a top-down perspective view of a luggage, showing my new design;

FIG. 2 is a front elevational view thereof;

FIG. 3 is a side elevational view thereof;

FIG. 4 is a bottom plan view thereof;

FIG. 5 is a top plan view thereof;

FIG. 6 is a front perspective view thereof, shown in an open state with the top compartment unzipped;

FIG. 7 is another front perspective view thereof, shown in an open state with the top and bottom compartments zipped; and,

FIG. 8 is another top-down perspective view thereof, shown in an open state with the bottom compartment unzipped.

The broken lines depicting stitching on the luggage form part of the claimed design. The surface ornamentation showing white markings of clothing and accessories depict environmental subject matter that form no part of the claimed design.
